UNITED STATES PATENT OFFICE

CLEO H. KIDWELL, OF DONGAN HILLS, NEW YORK, ASSIGNOR TO KIDWELL & COMPANY, INC., A CORPORATION OF NEW YORK

DESIGN FOR A BOX

Application filed July 31, 1928. Serial No. 27,646. Term of patent 14 years.

To all whom it may concern:

Be it known that I, CLEO H. KIDWELL, a citizen of the United States, residing at Dongan Hills, in the county of Richmond and State of New York, have invented a new, original, and ornamental Design for a Box, of which the following is a specification, reference being made to the accompanying drawing, forming a part thereof.

In the drawing

Fig. 1 is a perspective view showing the front, top and one side of the box embodying my new design; and

Fig. 2 shows a back view of the same.

I claim:

The ornamental design for a box as shown.

CLEO H. KIDWELL.
